UNITED STATES PATENT OFFICE.

WILLIAM H. BELL, OF NEW ORLEANS, LOUISIANA.

APPARATUS FOR PROTECTING THE BANKS OF STREAMS.

SPECIFICATION forming part of Letters Patent No. 239,920, dated April 12, 1881.

Application filed December 20, 1880. (No model.)

To all whom it may concern:

Be it known that I, WILLIAM H. BELL, a resident of the city of New Orleans, parish of Orleans, and State of Louisiana, have invented 5 a certain new and useful Improvement in Apparatus and Method for Protecting the Banks of Streams; and I do hereby declare the following to be a full, clear, and correct description of the same, reference being had to the 10 annexed drawings, making a part of this specification.

This invention relates to means for fending off currents, breaking eddies, preventing erosion of banks, and causing alluvial-bearing 15 streams to deposit sediment over, between, and in the fenders, by which process the banks will be protected and accretions formed.

My invention consists in a fender for submersion, constructed of brush, bagasse, or other 20 suitable material, arranged in layers having the shape of a cross.

My invention further consists in a fender-block composed of wooden frames, in which brush or bagasse or other suitable material is 25 arranged in layers crosswise, in combination with weighted material between the same.

My invention further consists in means, hereinafter described, for lowering the fender-blocks.

30 In order that my invention may be more readily understood, reference is had to the accompanying drawings, in which—

Figure 1 represents my method or mode of laying or connecting the layers of brush or 35 other suitable material crosswise. Fig. 2 represents a complete cross-shaped fender, secured together by means of fender-frames, in condition for submersion. Fig. 3 is a cross-section of a river-bank covered with a number 40 of the fenders. Fig. 4 is a plan view of a river or stream with a line of fenders or fender-blocks along one bank thereof. Fig. 5 is a perspective view of a means for lowering the fender-blocks in position.

45 In building my cross-shaped fenders for submersion, a suitable frame for securing the material in position is desirable, and to accomplish this object I construct what is known as a "fender-frame." This fender-frame consists 50 preferably of the two cross-frames F, secured at certain distance apart by means of vertical

bars g, pinned to the ends of the cross-frames, as seen in Fig. 2 of the drawings. In some cases a rectangular frame, as seen in Fig. 1 of the drawings, may be employed for accomplishing the same object. This frame consists of wooden frames, each of which is composed of four pieces, a b c d, with mortised ends, and these frames, when put together to secure the fender, are securely fastened by means of keys 55 or wedges e e', as seen in Fig. 1 of the drawings. These fender-frames, which are either square or triangular, as before stated, may be made of any desired size or length to receive the brush, bagasse, or other material used for 60 filling. This filling material, which consists of undergrowth brush, cane, or bagasse, is arranged in the frames in cross-layers—that is to say, the layers are arranged at right angles to each other in the shape of a cross—and 65 weighted with bags of sand or other heavy material, which are preferably placed inside of the filling, as indicated by the letter f, in dotted lines in Figs. 1 and 2 of the drawings. When the required size of fender is made, the 70 top frame is adjusted in position over the filling and securely keyed, thus completing the 75 fender for submersion.

A fender of the construction and form as hereinbefore described and shown will prevent it from being rolled about under the force 80 of currents and eddies.

The blocks are lowered from barges to the bed of the river at any desired locality, by a device consisting of four self-acting hooks, g' 85 h i k, suspended from a double T-frame, the latter raised or lowered by means of chains l l'. The hooks are at sufficient distance apart to prevent the fender-blocks from turning and altering their positions during their descent to 90 the bed of the stream, and to release themselves by swinging clear of each block after it has been placed in proper position. This lowering device (seen in Fig. 5 of the drawings) is specially designed for the rectangular frame 95 shown in Fig. 1 of the drawings.

In the method of submerging the fenders, I commence at the bottom of the stream and build upward in a single course on the sloping bed of the stream toward the shore or bank, 100 so as to allow a deposit to fill and cover the fenders before the second course is laid or

placed. The width of base and height of each line of fenders, as well as distance apart, is to be determined by the local necessity.

Having thus described my invention, what I claim as new, and desire to secure by Letters Patent, is—

1. A fender-block for submersion, constructed of brush, bagasse, or other suitable material, arranged in layers crosswise, having the shape 10 of a cross, substantially as shown, and for the purpose set forth.

2. The fender-blocks herein described, composed of wooden frames, in which brush, bagasse, or other suitable material is arranged in

layers crosswise, in combination with weighted 15 material between the same, for the purpose specified.

3. The means herein described for lowering the fender-blocks, the same consisting of a double T-frame furnished with self-acting 20 hooks *g' h i k*, the whole raised or lowered by means of chains *l l'*, as specified.

In testimony whereof I have hereunto signed my name.

W. H. BELL.

In presence of—

J. C. HUBBELL,
J. C. CLARKE.
